UNITED STATES PATENT OFFICE

2,672,131

COOLING SYSTEM

Everett N. Wood, Cedar Rapids, Iowa

Application May 16, 1950, Serial No. 162,276

7 Claims. (Cl. 123—41.08)

1

This invention relates in general to internal combustion engine cooling systems and in particular to apparatus for greatly reducing aeration of the coolant fluid.

The use of internal combustion engines has reached the point where everyone comes in contact with them daily. The modern automobiles, trucks, and diesel locomotives are a few examples of the general use of such engines. The operation of internal combustion engines presents the problem of cooling them. Liquid cooling systems are most commonly used. The liquid is circulated through cooling passages of the engine by thermosyphon or other suitable means. As the engine is started it begins to warm up and thus causes expansion of the coolant fluid.

If there is no provision to allow for this expansion, the fluid will be lost from the cooling system through a suitable overflow outlet. When the engine has cooled somewhat, it will suck the coolant to a lower level and this usually occurs rather violently. This sucking mixes air with the fluid and pulls it down into the engine where it causes "hot spots." It is this aeration which causes overheating of the engine and excessive loss of fluid. It is very desirable therefore, to prevent the loss of fluid from the cooling system and also to prevent the coolant system from becoming aerated.

It is an object of this invention to provide an internal combustion engine cooling system which eliminates the aeration of the coolant fluid.

Another object of this invention is to provide means for reducing the occurrence of high temperature "hot spots" and changing them into low mean average temperature areas.

Yet another object of this invention is to increase the efficiency of operation of an internal combustion engine.

Still another object is to provide means for eliminating aeration and loss of the fluid due to expansion, evaporation or heat surging caused from aeration of the cooling system.

Another object of this invention is to control the temperature in the engine block and head so that "hot spot" temperatures are held to a constant, uniform temperature thus giving a higher motor performance due to the elimination of detonation.

To prolong the life on an internal combustion engine by preventing high temperature "hot spots" which cause breakdown of the engine lubricant is still another object of this invention.

A feature of this invention is found in the provision of a surge tank connected to the fluid

2

reservoir of a cooling system wherein the overflow from the reservoir may pass through a first passage to a surge tank upon expansion of the fluid and wherein a second passageway having a one-way valve allows the fluid to pass from the surge tank to the reservoir when a negative pressure differential exists between the two tanks.

Further objects, features, and advantages of this invention will become apparent from the following description and claims when read in view of the drawings, in which.

Figure 1 is a perspective view of the front end of an automobile showing applicant's invention installed therein;

Figure 2 is a sectional view taken on line 2—2 of Figure 1 showing the surge tank and reservoir with the fluid passages interconnecting therein;

Figure 3 is a cutaway, sectional, perspective view of the interconnecting passageways of this invention;

Figure 4 is a sectional view of the valve assembly of this invention; and,

Figure 5 is a detailed view of a baffle plate.

Figure 1 illustrates the front end of an automobile, designated generally as 10, which has an engine 11, radiator 12, and coolant system tank 13. A pipe 14 connects the cooling passages of the engine 11 with the tank 13. A second tube, not shown, connects the bottom of the radiator to the engine cooling system and the fluid is circulated by a pump through the cooling system.

The coolant system tank 13 is divided into two compartments to provide a fluid reservoir 16 and a surge tank 17. This is best shown in Figures 2 and 3. A partition 18 extends from one wall 19 of the tank 13 to the opposite wall 21. The partition 18 has downwardly extending portions 22 and 23 adjacent the walls 19 and 21. The portion 22 slants generally upwardly toward each end of the tank 13, whereas the portion 23 extends generally downwardly toward the ends 24. An end portion 26 of the partition 18 is curved downwardly so that as the reservoir 16 is filled with fluid no air will be trapped in the portion 22 or 26, but it will flow upwardly to portion 23 in the middle of the tank.

A filler neck 27 is attached to the top of tank 13 and extends partially into the tank and engages the partition 18. An opening 28 is formed in the bottom 15 of the filler neck 27 and mates with an opening 29 formed in partition 18. The upper end 29 of the filler neck is threaded for receiving thereon an air-tight cap 30 shown in Figure 2.

Extending downwardly from the bottom 15 of the filler neck 27 is a two-way passage tube, or valve line, 31. It is shown in detail in Figure 4. One end is formed with an external hexagonal head 32 and adjacent the head are external threads 33. The opposite end 34 of the tube has retaining means 36 mounted therein. The spring retainer 36 is G-shaped and is retained in a groove 37 formed in the tube 31.

A partition 38 extends across the passageway of the tube 31 adjacent the end 34 and an opening 39 is formed transversely through the wall of the tube adjacent partition 38 to form an opening for the fluid passing through the head 32. A second opening 41 is formed transversely through the tube 31 to allow fluid communication through the end 34 of the tube.

A float valve 42 is retained between the retainer 36 and a valve seat 43 formed adjacent the partition 38. The valve 42 is a ball and has a specific gravity slightly less than that of the coolant fluid being used. If water is being used as the coolant, applicant has found that polyethylene is a very satisfactory material for the ball 42. This material has a specific gravity of 0.92 and thus floats in water or any mixture which has a specific gravity greater than 0.92. The ball 42 should not have any affinity for oil, alcohol, or coolant system sediment.

The tube 31 is threadedly received through the bottom 15 and extends downwardly through the surge tank 17 and its opposite end 34 extends through the partition 18 and is in communication with reservoir 16. The connections between the tube 31 and the bottom 15 and partition 18 are air tight.

The openings 39 and 41 open into the surge tank 17.

A baffle plate 45 is formed with a central opening 46 which fits about tube 31 adjacent and above the opening 39. The tube is loosely received through opening 46. The plate 45 may be formed with openings 48. It is shown in detail in Figure 5 and comprises a central portion 47 which is formed with a central opening 48 for receiving the tube 31 therethrough. Ends 49 extend downwardly at either side of the baffle plate and as shown in Figure 2 do not engage the bottom of the partition 18. The inlet tube 14 extends through the wall of the reservoir 16 and the projecting portion 50 serves somewhat as a baffle to prevent scrubbing and turbulence in the reservoir.

In operation, the cap 39 is removed and liquid, as for example, water, is poured into the system. The water flows through the opening 20 and into the reservoir 16 before passing into the radiator tubes 51 and into the engine. When the reservoir is full more water is added until the filler neck 27 is filled to a level even with the upper end 32 of the tube 31. Water then flows down tube 31 and into the surge tank 17 through the opening 39. It is to be understood that water does not enter the surge tank through the lower end of tube 31 because the ball 42 floats up against the valve seat 43. Water is poured into the surge tank until it is full. Then the cap 39 is screwed on and the engine may be started.

As the engine warms up, the water expands and flows from the reservoir to the surge tank 17 by passing from the filler neck 27 through the opening 20 and down through the tube 31 and out the opening 39. The ball 42 still prevents fluid from entering the lower end of the tube 31, and out the opening 41. The thermal expansion causes fluid to pass out of the surge tank

17 through an overflow pipe 44 connected to the top of the surge tank if the surge tank is too full.

When the engine cools slightly and draws water from the reservoir 16, negative pressure is exerted on the ball 42 and it drops and allows water from the surge tank 17 to satisfy the need of the engine. In case of a violent collapse water will be drawn up tube 31 from the chamber below the plate 45 through the openings 48 into cap 20 as well as past ball 42. The engine demand for water is sometimes very violent and air would be drawn into the engine if it were not for the structure of applicant's invention. When sufficient water has been supplied to the engine, the valve 42 closes until more water is needed.

The delicate balance of the ball 42 prevents it from becoming clogged or stuck due to sediment or oil. It moves very rapidly from the valve seat 43 to the retainer 36 and thus forces foreign matter out of the tube 31.

The baffle plate 45 about the tube 31 prevents air from being drawn into the fluid when the engine is exerting negative pressure on the reservoir 16.

The reservoir 16 is completely filled with water at all times as well as the filler neck 27 and the tube 31. The depth of water in the surge tank should be maintained at least one-half full at all times. When the fluid is first added to the system, the level should be frequently checked and more added until all the air is out of the fluid. Applicant has found that it requires approximately 24 hours to completely deaerate the cooling fluid. Once it has been completely deaerated, however, very little fluid will have to be added. Applicant has operated an automobile equipped with this invention for a year with a solution of alcohol and water and loss of fluid has been negligible. Extensive experiments have shown that the cause of loss of fluid and excessive heating of the engine is aeration of the fluid. Air drawn into the engine accumulates to form bubbles and prevent the fluid from contacting the hot walls to cool them. This results in a breakdown of the lubricant and excessive wear and failure of the engine. The extreme heat thus developed, blows the fluid from the radiator. Applicant's invention prevents aeration by furnishing a reservoir which is completely full of liquid and thus, no air can be drawn into the cooling system of the engine as fluid is demanded. The baffle plate 45 prevents air from being drawn into the system from the surge tank past the valve 42 or up valve line body 31.

55 The cooling system may be maintained above atmospheric pressure if desired, by the addition of a pressure release valve in overflow tube 44. The system operates substantially in the same manner as when the tube 44 is open to the atmosphere.

It is seen that this invention provides means for efficiently cooling an engine without loss of coolant fluid or aeration.

Although this invention has been described with respect to a preferred embodiment thereof, it is not to be so limited as changes and modifications may be made therein which are within the full intended scope of the invention as defined by the appended claims.

70 I claim:

1. Apparatus for controlling the temperature of an internal combustion engine comprising a reservoir connected to the cooling system of said engine and supplying fluid thereto, a surge tank attached above said reservoir, a first fluid inlet

connecting the upper portion of said reservoir with the surge tank, a second passageway connecting the lower end of said surge tank with a lower portion of said reservoir, and a one-way ball valve within said second passageway for preventing fluid from flowing from said reservoir into said surge tank.

2. In an apparatus according to claim 1 wherein in said valve comprises a valve seat, and a ball valve of a material which has a specific gravity slightly less than the specific gravity of the fluid used in the cooling system.

3. Apparatus for cooling an internal combustion engine comprising a reservoir connected to the cooling system of said engine having a generally curved top portion, a surge tank attached to the top of said reservoir, a filler neck connected to said surge tank extending into the said reservoir, a first fluid passage connecting the top portion of said reservoir with said surge tank, and a second passageway connecting the bottom of said surge tank with said reservoir, a one-way valve within said passageway preventing fluid from flowing from said reservoir into said surge tank and the top portion of said reservoir formed so that gases will be forced upward to said first passageway as the reservoir is filled with fluid.

4. Apparatus for preventing aeration of an engine cooling system comprising, a radiator top tank connected in said cooling system, a partition within said tank dividing it into a reservoir and a surge tank, a first fluid passageway connecting the top of said reservoir with said surge tank, a second passageway connecting the bottom of said surge tank with said reservoir, a one way valve within said second passageway allowing fluid to flow from the surge tank to the reservoir when a negative pressure exists between them, an overflow tube attached to the top of said surge tank, and a pressure release valve within said overflow tube adjustable to a predetermined pressure.

5. In a system according to claim 4 wherein said one way valve comprises a float valve which has a specific gravity slightly less than that of the cooling fluid.

6. In a system according to claim 4 wherein a baffle plate is attached to the surge tank about the outlet of said second passageway to prevent air being drawn into the cooling fluid as it is withdrawn from the surge tank.

7. Apparatus for preventing aeration of an engine cooling system comprising, a radiator top tank connected in said cooling system, a partition within said tank dividing it into a reservoir and a surge tank, a first fluid passageway connecting the top of said reservoir with said surge tank, a second passageway connecting the bottom of said surge tank with said reservoir, a one-way ball valve within said second passageway allowing fluid to flow from the surge tank to the reservoir when a negative pressure exists between them, the ball of said ball valve formed of material with a specific gravity slightly less than the specific gravity of the cooling fluid, and a baffle plate mounted in the surge tank above the opening into the second passageway.
